(57) **CLAIM**

The ornamental design for a refuse container, as shown and described.

DESCRIPTION

FIG. 1 is a front-top-right perspective view of a refuse container showing our new design;

FIG. 2 is a front elevational view thereof;

FIG. 3 is a right side elevational view thereof;

FIG. 4 is a top plan view thereof;

FIG. 5 is a bottom plan view thereof; and,

FIG. 6 is a rear elevational view thereof.

The broken lines in the figures are for illustrative purposes only and form no part of the claimed design.
